VEHICLE JACK

Tom C. White, Billings, Mont.

Application June 25, 1934, Serial No. 732,313

12 Claims. (Cl. 254—133)

This invention relates to lifting jacks, and, more particularly, to elevating jacks for vehicles wherein the jack head or elevating platform is self-centering.

5 An object of the invention is to provide a jack head which will center itself under the vehicle axle without the necessity of the operator crawling beneath the car to place the head in position.

A still further object of the invention is to construct a self-centering jack-head which will become operative even though the head strikes the axle at an angle and one which will insure the centering of the axle directly over the elevating rod and also prevent the car from falling off the 15 jack-head.

In the drawings Fig. 1 is illustrative of a conventional screw type jack provided with the novel self-centering head.

Fig. 2 is an enlarged side elevation of the head 20 supporting the vehicle axle.

Fig. 3 is a vertical cross-section of the head illustrated in Fig. 2.

Fig. 4 is a similar head mounted on a rack bar type of jack.

25 Fig. 5 illustrates the self-centering head in combination with a hydraulic jack.

Fig. 6 is a top plan view of the self-centering head.

The present invention is primarily a jack-head 30 or elevator platform applicable to all types of vehicle lifting jacks, whether they be operated by an elevating screw, a rack bar, or a hydraulic pump mechanism. In Fig. 1 the invention is shown as applied to a conventional screw type jack 35 which comprises a removable ground-engaging platform 1 in which is bracketed the enlarged base 2. Integrally formed with the base 2 is hollow column 3 in which is telescoped screw 4. Suitable pinions 5 and 6 are mounted interiorly of 40 casing 7 in the upper portion of the column 3, with the screw 4 threaded through the center of pinion 5. The pinion 6 is rotated by a detachable shaft 8 which terminates in an extension handle.

45 Rigidly affixed to the upper end of the screw 4 is the self-centering jack-head or elevator platform 10.

Referring to the several views, and particularly to the top plan shown in Fig. 6, it will be seen 50 that the head 10 consists essentially of an elliptically shaped plate having all of its surface edges rounded, so that no portion of the head presents a sharp edge.

Referring to Figs. 2 and 3, it will be observed, 55 in side elevation and in vertical section, the ellip-

tical plate 10 is bent or curved upwardly from its midpoint, so that the ends 11 and 12 are arcuately disposed and the head is substantially concave. The head 10 is mounted or affixed on the jack elevating rod by a screw, rack bar, or hydraulic plunger, in a slightly off-center position. The forward portion 13 of the elliptical plate 10 is of considerably greater radius than the rear portion 14. In forming the head the front end 12 is bent or pressed outwardly at the 10 portion 13 to form an offset nose or cam surface 15 on the upper side of the plate. Aside from mounting the plate 10 off center, the larger forward end 12 is bent upward to a greater height from the horizontal plane of the elevating rod 15 than is the rearward end 11.

Referring to Fig. 1, "B" denotes an axle, while "A" denotes an automobile spring hanger, or other portion, of the running gear of an automobile, against which the jack-head is contacted. When 20 the rounded nose 15, or any other forward portion of the head 10, strikes the axle "A", it will turn or swivel on the screw 4 and swing the lower end 11 of the head thereunder.

Fig. 2 is a view of the axle "B" after being centered over the head 10 (in reverse position from Fig. 1). It should be borne in mind that it is not necessary for the forward edge of the cam face 15 to strike directly on the axle, but any portion of the nose may contact therewith and 30 the jack-head will immediately and automatically turn and center itself. Thereupon, continued operation of the elevating mechanism will lift the car.

Fig. 4 illustrates the self-centering head swivelled on a non-rotating lifting rod by means of collar 20 and set screw 21 which rides in an annular groove 22 formed in the upper end of the rack bar 23.

Fig. 5 is directed to the attachment of the 40 self-centering head 10 to a hydraulic type jack. The head is affixed to vertical adjusting screw 25 carried by piston 26 which is elevated through the medium of fluid in cylinder 27, the fluid being compressed by pump 28. The primary adjustment to secure the approximate height being made by elevating the screw 25, the jack is then merely pushed under the car by its extended handle. After becoming centered, as before described, the pump 28 is operated to elevate piston 50 26 and lift the vehicle.

It will be understood by those skilled in the art that the jack-heads or platforms illustrated in the drawings and defined in the appended claims may be constructed separately and at- 55

tached to any type of conventional vehicle jack.

What I claim is:

1. A self-centering, lifting head for jacks comprising an upwardly curved, elliptically shaped plate, one end of the curved plate rising to a greater height than the other end of the said plate.

2. A lifting head for jacks comprising an upwardly curved, elliptically shaped plate having all of its surface edges rounded, the upward curve of one end of said plate being of less height than the other end thereof.

3. A lifting head for jacks comprising an upwardly curved, elliptically shaped plate, the surface edges of said plate being rounded and in which the curvature and height of one end of said plate is greater than the curvature and height of the opposite end of said plate.

4. In a vehicle jack, an elevating rod, a rotatable, axle-engaging head, said head consisting of an arcuately shaped, elliptical plate supported slightly off center on the upper end of said rod, and a rounded offset section formed on one portion of said arcuate plate and adapted to contact with the axle of a vehicle and rotate said head to engaging position.

5. In an elevating device, a vertically movable rod, an elliptical head eccentrically affixed to said rod, said elliptical head being arcuately bent to present its ends in elevated position above the horizontal plane of the midsection of said head, one of said ends being bent to a higher elevation than the other of said ends, and a pressed-out portion forming a cam face on the underside of said higher elevated end.

6. In a vehicle jack, an elevating rod, a concave plate mounted for rotation on or with said rod, said plate being of substantially elliptical shape, the end of the elliptical plate having the greater radius rising to a greater height above

the end of said rod than does the end of the plate having the smaller radius.

7. An axle-engaging head for vehicle jacks comprising a rounded edged and ended plate, the end portions of the plate being bent upwardly with one of the said upwardly bent ends rising to a greater elevation than the other of said ends, and an outwardly extending nose portion on the outer surface of the end portion having the greater height.

8. In a vehicle jack, an elevating rod, a self-locating lifting head attached thereto, said head comprising a low vehicle engaging portion and an upwardly extending vehicle contacting portion.

9. In vehicle jacks, a self-centering head therefor, said head including a platform section adapted to support the weight of a vehicle thereon, and an upstanding section adapted to contact and be arrested by the portion of the vehicle to be lifted prior to the actual lifting thereof.

10. In a self-centering and self-arresting head for vehicle jacks, a weight supporting platform integrally formed in one portion of said head, and an upwardly extending offset portion integrally formed in another portion of said head.

11. A vehicle jack including a lifting rod, a self-centering head attached to the upper end thereof, said head having a vehicle supporting portion substantially in the plane of the upper terminus of said lifting rod and head centering portion in a plane above the upper terminus of said rod.

12. A vehicle jack including a lifting rod, a self-locating lifting head attached to the upper end thereof, said head comprising a base plate adapted to engage a portion of a vehicle, the central portion and one end of said plate being in a substantially lower horizontal plane than the opposite end of said plate.

TOM C. WHITE. 40
